COMBINED NOZZLE AND COUPLING FOR GARDEN HOSES

Byron F. Lohmar, 108 S. Saturn Ave., Clearwater, Fla.
Filed Aug. 18, 1961, Ser. No. 66,417

Term of patent 14 years

(Cl. D91—1)

FIG. 1.

FIG. 2.

FIG. 3.

FIG. 4.

FIGURE 1 is an end elevational view of the discharge end of my combined nozzle and coupling for garden hoses embodying my new design;

FIGURE 2 is a side elevational view thereof;

FIGURE 3 is an end elevational view of the input end thereof;

FIGURE 4 is an enlarged transverse, fragmentary, detail cross-sectional view thereof taken on the vertical plane of line 4—4 of FIGURE 2, looking in the direction of the arrows.

I claim:

The ornamental design for a combined nozzle and coupling for garden hoses, as shown.
